The ornamental design for a display frame, as shown and described.

DESCRIPTION

FIG. 1 is a perspective view of the frame.

FIG. 2 is a front view of the present invention as shown FIG. 1.

FIG. 3 is a back view thereof.

FIG. 4 is a right side view of FIG. 1.

FIG. 5 is a left side view of FIG. 1.

FIG. 6 is a top view of FIG. 1.

FIG. 7 is a bottom view thereof; and,

FIG. 8 is a front view of a hanging single tier display frame with adornments attached thereto.

The broken lines showing a hanging device and adornments are included for the purpose of illustrating environmental structure and form no part of the claimed design. The wavy broken lines represent break lines and form no part of the claimed design.

In addition, the display frame is shown with a symbolic break in its width, represented by the wavy broken lines. The appearance of any portion of the article between the wavy broken lines forms no part of the claimed design.
